UNITED STATES PATENT OFFICE.

ROBERTA W. HENDRIX, OF CHICAGO, ILLINOIS.

DOLL WALKER.

Application filed August 18, 1919. Serial No. 318,129.

To all whom it may concern:

Be it known that I, ROBERTA W. HENDRIX, a citizen of the United States of America, residing at Chicago, in the county of Cook 5 and State of Illinois, have invented certain new and useful Improvements in Doll Walkers, of which the following is a specification.

This invention relates to improvements in 10 doll-walkers, and the principal objects of my improvement are, first, to provide an improved supporting frame, and, second, the provision of figure-supporting devices suitable for dolls of different sizes and lengths.

15 This invention is an improvement in connection with the construction disclosed in my pending application filed May 19, 1919, Serial #298,218.

With the above and other objects in view, 20 my invention consists in the novel features and in the novel combination and arrangement of parts, illustrated in the accompanying drawings forming a part of this specification, and particularly pointed out in 25 the claims hereunto appended; it being understood that changes, variations and modifications in the details of the invention within the scope of the claims, may be resorted to without departing from the spirit or sacrificing any of the advantages thereof.

In the drawings,

Figure 1 is a perspective view of the doll-walker with parts of the doll figure,

Figure 2 is a perspective view of the supporting frame and the figure-supporting device,

Figure 3 is a sectional plan of the doll-walker,

Figure 4 is a detail of the engaging ends 40 of the supporting frame and the figure-supporting device,

Figure 5 is a cross section on line 5—5 on Figure 4,

Figure 6 is a similar view on line 6—6 on 45 Figure 4,

Similar numerals and letters refer to similar parts throughout the several views.

The capital letter A denotes a supporting frame, preferably made of two lengths of 50 sheet metal and their free ends fixed together at 7, 7, one length being bent intermediate its ends to present side members 8, 8, and what is termed a figure supporting base 9, being formed by a quarter turn of the sheet metal relative to the side members 7, 7, and by the use of a suitable die the loops

10, 11, are forced in opposite directions to afford a space 12. The other one of said lengths of sheet metal being bent intermediate its ends to present side members 13, 13, and a loop-member 14, which is formed by about an eighth of a turn of the sheet metal relative to the side members 13, 13, and by the employment of a suitable tool the loops 15, 16, are forced oppositely leaving an opening 17, to receive one end of the handle 18, for operating the doll-walker.

A crank shaft 19, having cranks 20, is journaled in the side members 13, 13, at 21, 22, the free ends 23, 24, of the crank shaft being 70 fixed to the wheels 25, 26, so that rotation of the wheels 25, 26, operates the crank shaft 19 and the links 27 to reciprocate the feet or leg portions 28, to which they are attached.

An important part of my invention is 75 what is termed a figure-supporting-device 29 which comprises a length of wire, preferably steel, bent intermediate its ends to present diverging portions 30, 30, terminating at the free ends in figure-engaging half circles 80 31, 31, disposed at right angles to the planes of the parallel portions 30, 30.

The half circles 31, 31, (see Figure 1) 85 pass around the waist of the doll 31 under its clothes and the wedging-link 32 serves to fix the device 29 at a proper altitude with reference to the supporting frame A. Tape 33 secured to one end of each link 27 serves to fasten the links 27 and leg portions 28 90 of the doll.

To mount the figure, the figure-supporting device 29 may be withdrawn from the space 12 and applied to doll with the half circles 31 about the waist of the doll, then the doll placed in position by inserting the lower end 95 34 of the figure-supporting device in the space 12 and lowered sufficiently when the wedging member 32 is pushed into position to firmly support the figure or doll.

The dished disk 35 on the inside of each wheel serves to prevent the wheels 25, 26 100 interfering with the supporting frame A.

By thus showing and specifically describing the embodiment herein of my invention, I do not intend to restrict the range of 105 equivalents more than is made necessary by the prior state of this art.

Having thus fully described my invention, what I claim as new, and desire to secure by Letters Patent, is:

110 1. In a device of the character described, a frame having an upstanding member at

the front end and having a forward opening recess at the lower part, a crank shaft journaled in the lower part extending across said recess, and having cranks therein, and carrying wheels on said shaft, the frame having on its upstanding part means for mounting a walking figure for supporting the frame at the forward end, and pitman links connected at their rear ends to the 10 cranks of the crank shaft, and at their forward ends to the limbs of the walking figure; and means for manually propelling the structure on its wheels, whereby the walking figure in its walking movements, supports the forward end of the structure.

2. In a device of the character described, a frame comprising a forwardly-opened fore and aft extending member, and a downwardly open up and down extending member, the 20 two members being rigidly united at the forward open end of the first member, and the bottom open end of the second member; a cranked shaft journaled in the fore and aft extending member at a substantial distance 25 back of the open forward end thereof, with its cranks within the opening of the sides thereof, and carrying wheels on said shaft; the up and down extending member having means at its upper closed end for holding a

walking figure tall enough to reach the plane 30 of tread of the carrying wheels, and thereby uphold the frame at the forward end; pitman links connected at their rear ends respectively with the cranks of the crank shaft, and at their forward ends adapted to be connected 35 with the limbs of the walking figure, and handle means for manually propelling the structure on said wheels; whereby such propulsion causes the walking figure to walk while supporting the structure at the front. 40

3. In mechanism of the class described, the combination of a wheel supported frame having an upstanding inverted U-shaped section formed of a metal strip and having the central portion of its arm connection turned to 45 lie substantially in a plane extending longitudinally of the arms and provided with spaced parallel slits transverse the section, the portion of the arm connection between the slits being curved oppositely to the portion above and below the slits to provide a 50 socket formation, a figure supporting device engaged in said socket formation, and a crank device for connecting the supporting wheels to parts of a supported figure. 55

In testimony whereof I affix my signature.

ROBERTA W. HENDRIX.
